BY Joseph B. Gardner

ATTORNEY.

UNITED STATES PATENT OFFICE

112,953

DESIGN FOR AN EGG BEATER

Kenneth B. Van Woert, Sr., Oakland, Calif.

Application April 11, 1938, Serial No. 76,417

Term of patent 14 years

To all whom it may concern:

Be it known that I, Kenneth B. Van Woert, Sr., a citizen of the United States and a resident of the city of Oakland, county of Alameda, State of California, have invented a new, original, and ornamental Design for an Egg Beater, of which the following is a specification, reference being had to the accompanying drawing, forming part thereof.

I claim:

The ornamental design for an egg beater, substantially as shown.

KENNETH B. VAN WOERT, SR.
